SANDWICH PICK OR THE LIKE

Homer Lynn, Johnstown, Ohio, assignor to Harold Leonard & Co., Inc., New York, N.Y.

Filed Mar. 2, 1966, Ser. No. 1,239

Term of patent 14 years

(Cl. D86—10)

FIG. 1

FIG. 2

FIG. 3

FIG. 4

FIG. 1 is a perspective view of a sandwich pick or the like showing my new design;

FIG. 2 is a front view thereof;

FIG. 3 is a side view thereof; and

FIG. 4 is a plan view thereof.

I claim:

The ornamental design for a sandwich pick or the like, substantially as shown.
